PENNSYLVANIA

FABRICATION OF EMBOSSED METALLIC PLATES

Application filed March 30, 1928. Serial No. 265,928.

This invention relates to fabrication of metallic tread or wear plates of a type characterized by roughened surfaces formed by multifold projections or embossments. More 5 specifically speaking, my invention is concerned with production of tread plates from sheet metal of lighter gages. Considerable difficulty has been experienced heretofore in the fabrication of light gage embossed plates 10 due to the tendency of the metal to puncture, fracture or buckle incidental to the setting up of the surface embossments by passage between opposing die rollers. The aim of my 15 invention is to overcome the difficulty referred to, and this I accomplish by concurrently passing several blank metallic sheets between the die rollers so as to secure a cushioning effect with assurance of uniform displacement of the metal to the avoidance of 20 puncturing, fracturing or buckling, and with attendant production of as many finished plates having embossments distinguished by variation in sharpness of outline.

With reference to the drawings, Figs. I and 25 II illustrate strips of two different kinds of embossed plates simultaneously fabricated in accordance with my invention.

Fig. III shows a fragment of the strip of Fig. I on a larger scale.

30 Fig. IV is a detail cross section taken as indicated by the arrows IV—IV in Fig. III.

Figs. V and VI are views similar to Figs. 35 III and IV, of the strip illustrated in Fig. II.

Fig. VII shows a cooperating pair of die rollers which I employ to forge the embossed plates; and,

40 Fig. VIII is a fragmentary detail sectional view, to a still larger scale, showing the operation of the die rollers.

In carrying out my invention I employ a 45 pair of die rollers such as illustrated at 10, 11 in Figs. VII and VIII. As shown, one of these die rollers—which may for convenience be termed the “pattern” or “impress” roller—

present instance diamond or lozenge shaped) corresponding to the configuration of the projections or embossments desired in the finished plates; while the opposing roller is plain surfaced. Between these rollers 10, 11 50 I concurrently pass several blank metallic sheets 13, 14—for example two, which may be of uniform gage as shown at the right of Fig. VIII—in superimposed relation, the sheets being preferably pre-heated to facilitate ready forging of the metal. As the sheets 13, 14 traverse the nip of the rollers 10, 11, it will be seen that the metal of the upper sheet 13 is forced into the recesses or indentations 12 of the upper roller 10, and that 55 uniform flow of the metal of the upper sheet 13 is insured by the cushioning effect of the lower sheet 14 running against the plain roller 11. It will moreover be noted that a corresponding compensative displacement of the 60 metal of the lower sheet 14 takes place at the same time. As a consequence of the described action, the upper of the two plates 13, 14 takes on a more or less corrugated cross section, and is characterized with sharply defined surface projections 16 (Figs. I, III and 65 IV) by virtue of having run in direct contact with the upper or impressed roller 10. The lowermost plate 14 on the other hand remains perfectly flat throughout, i. e. with a 70 smooth bottom surface as a consequence of contact with the plain roller 11 and is further distinguished by virtue of having embossments 17, which, as shown in Figs. II, V and VI, are more rounded and thus more vaguely 75 defined than those of the first plate 13. In this very simple manner I am able to roll—without danger of puncture, fracture or buckling—very thin metallic sheets, and concurrently produce embossed plates in multiple 80 distinguished by roughened surfaces differing in sharpness as regards the outlines of their projections or embossments, but both highly attractive and neat in appearance. The 85 number of sheets, rolled at one time may vary 90

in accordance with the gage of the metal, as well as with regard to the proportioning and character of the surface projections. The concurrent rolling of two sheets as herein shown and described is therefore to be regarded as illustrative in a general way rather than specific.

For the purposes of running boards for motor vehicles, stair treads, etc. the embossed plates may be subsequently cut into strips of suitable width such as shown in Figs. I and II.

Having thus described my invention, I claim:

15. 1. The method of fabricating embossed plates by concurrently passing superimposed metallic blank sheets between a pattern-surfaced roller and an opposing plain-surfaced roller with production, by a single pass, of a

20 finished plate distinguished by sharply defined corrugations, with the other sheets cushioning said finished plate to the avoidance of puncturing and being themselves characterized by face projections of successively diminishing degree.

25 2. The method of fabricating embossed plates by concurrently passing several metallic blank sheets in superimposed relation between a pattern or impress roller and an opposing plain surfaced roller with production, by a single pass, of a corresponding number of finished plates distinguished by surface projections varying in sharpness of outline.

30 3. The method of fabricating embossed plates by concurrently passing several metallic blank sheets in superimposed relation between a pattern or impress roller and an opposing plain surfaced roller with production, by a single pass, of a corresponding number of finished plates, some of them corrugated, and all distinguished by surface projections varying in sharpness of outline.

35 4. The method of fabricating embossed plates by concurrently passing two metallic blank sheets in superimposed relation between a pattern or impress roller and an opposing plain surfaced roller, so that the sheet running in contact with the plain surfaced roller acts as a cushion for the other to insure uniform flow of the metal of the latter into conformity with the surface of the pattern or impress roller and at the same time prevent puncturing, fracturing or buckling.

40 5. The method of fabricating embossed plates by concurrently passing two metallic blank sheets in superimposed relation between a pattern or impress roller and an opposing plain surfaced roller with production, by a single pass of two finished plates, one of them corrugated and the other with a smooth back, and the two otherwise distinguished by surface projections varying in sharpness of outline.

45 6. The method of fabricating embossed plates by concurrently passing superimposed

blank metallic sheets between opposing pattern-surfaced and plain-surfaced rollers with impartation of impressions at intervals across all of said plates as well as sharply defined impressions in the plate running in contact with the pattern-surfaced roller and assurance of uniform displacement of the metal to the avoidance of puncturing, fracturing or buckling of said metal under the cushioning action of the other plates.

In testimony whereof, I have hereunto signed my name at Philadelphia, Pennsylvania, this 15th day of March, 1928.
